PULLING-OVER MACHINE.

1,117,301.

Specification of Letters Patent. Patented Nov. 17, 1914.

Application filed September 28, 1907. Serial No. 394,966.

To all whom it may concern:

Be it known that I, HARRIE A. BALLARD, of Boston, in the county of Suffolk and State of Massachusetts, have invented certain new and useful Improvements in Pulling-Over Machines, of which the following is a specification.

This invention has relation to machines for inserting fasteners, and more particularly to machines of the type illustrated in my application for Letters Patent, Serial No. 276,399, filed August 30, 1905, in which devices are employed for positioning an upper with respect to the last and inner-sole before the fastener is inserted through that portion of the upper which overlaps the innersole.

The present invention has for its object to provide certain improvements in machines of the general class named, for rendering them more accurate and efficient in operation, and to this end the invention consists in the features of construction and arrangement illustrated upon the accompanying drawings, described in the following specification, and set forth in the appended claims.

Referring to said drawings, Figure 1 represents a side elevation of a machine embodying the invention. Fig. 2 represents a front elevation of the same. Fig. 3 represents a side elevation of a part of the machine, and shows in dotted lines some of the parts hidden in Fig. 2. Fig. 4 represents the spring drive for the driver bar. Fig. 5 illustrates the worm gearing for rotating the hopper. Fig. 6 shows in side elevation and partially in section the front portion of the machine. Fig. 7 represents in plan view and partially in section, the mechanism for effecting the lateral movement of the delivery end of the raceway, the means for yieldingly mounting the picker and the gearing for effecting the rotation of the hopper. Fig. 8 represents a perspective view of the parts at the lower end of the raceway. Figs. 9, 10, 11 and 12 are sectional views illustrating the picker mechanism. Figs. 10, 11 and 12 illustrating the picking of a single fastener. Fig. 13 represents a longitudinal section through the same mechanism. Fig. 14 illustrates the finger for closing the entrance to the discharge throat of the raceway. Figs. 15, 16 and 17 (Sheet 2) are perspective views of

the picker mechanism. Fig. 18 is a vertical section of the delivery end of the raceway. Fig. 19 is a perspective view of brake members for stopping the machine. Fig. 20 illustrates the means for mounting the hopper. Fig. 21 represents a longitudinal section through the hopper. Figs. 22 and 23 illustrate the device for removing improperly placed tacks in the raceway.

The machine is preferably constructed with an upright column or support 10, to which is attached the frame or head 11, the said frame being of any convenient shape to receive the various operative parts. In the frame is journaled the main power shaft 12 to which rotation is imparted from a pulley 13 which is loose thereon. The pulley is adapted to be clutched to the shaft to effect its rotation through the complementary clutch members indicated at 14. The means for effecting the engagement of the clutch members is illustrated, as a whole, at 15, and is controlled by a lever 16. It is unnecessary to describe in detail the clutch or its operating mechanism, as the same are described in detail in my co-pending application Serial No. 351,814, filed January 11, 1907. In brief, however, the clutch members 14 are normally disengaged by a spring 17 which moves the pulley 13 endwise on the shaft 12. The clutch-setting mechanism 15 rotates with the shaft and normally tends to move the pulley in opposition to the spring 17 so as to operatively engage the complementary clutch member 14. The controller 16, which is pivoted on a stud 18, is movable into and out of engagement with the clutch-setting mechanism 15, and so long as it is disengaged, rotation is imparted to the shaft. When the controller is in the position shown on the drawing, it renders the mechanism 15 inoperative, allowing the spring 17 to separate the clutch members 14. Suitable brake mechanism, hereinafter described, is provided for arresting movement of the shaft 12, said mechanism, together with the clutch setting mechanism 15 and controlling mechanism, causing the shaft 12 to stop at the same point each time.

One embodiment of the present invention, which is illustrated upon the accompanying drawings, includes fastener-driving mechanism comprising primarily a tack-reservoir 20, a tack-driver 21, a tack-race 22 for conducting tacks from the reservoir to the

driver, and a tack-pick 23 for placing the tacks one by one in position to be driven. The driver is mounted on a driver bar 24 movable back and forth in guides 19 on the head. The upper end of the driver bar is connected with a spring driver 25 (see Fig. 4) having a spring 26 which actuates it so as to drive the tacks as hereinafter described. The driver bar is raised and held in an initially raised position by a flange 27 formed on a collar 28 affixed to the forward end of the shaft 12 (see Fig. 1). The flange 27 engages the under side of a block 29 rabbeted into the driver bar, and, as it rotates in the direction of the arrow in Fig. 2, its rounded end first engages the block 29, and then continues to rotate to its position of rest, which the same figure illustrates. Upon subsequent rotation of the shaft 12, the rear end of the flange 27 moves from under the block 29, whereupon the driver bar 24 is driven by the driver 25 toward the work held below. Descent of the driver bar is arrested by a buffer 30 attached to the upper end thereof and adapted to impinge against the guide 19.

A suitable brake mechanism appears in Figs. 1, 2 and 19, and in the form shown comprises a band or shoe 31, a yoke 32, and bolts 33 for connecting the shoe and yoke. The shoe 31 has an internal semi-circular face which is adapted to frictionally engage the exterior of the collar 28. The yoke 32 is pivoted to the head 11 by a stud 34, and its free end has a lip 35 which overhangs the block 29 on the driver bar. The shoe is adjustably connected to the yoke so that when the driver bar is raised to its initial elevated position, the free end of the yoke is correspondingly raised to such a position that the shoe is drawn tightly against the under side of the collar 28 and left in that position. By this means, momentum of the shaft 12 is overcome after the driving clutch 45 is released.

The illustrated form of tack reservoir 20 is shown as provided with trunnions 36 which are mounted in brackets on the head 11 so as to be able to oscillate therewith, and the tack-race being fastened rigidly to the reservoir is adapted to oscillate therewith. By reason of so mounting the tack-race, the delivery end thereof is adapted to coöperate with the stationary tack-pick to advance the tacks one by one into the discharge throat 37, as hereinafter described. The reservoir 20 is provided with a bearing for a rotatable shaft 38 on which is mounted a rotatable elevator 39 having buckets 40 for elevating tacks in the reservoir and discharging them upon the upper end of the tack-race. For rotating the elevator, the shaft 38 has affixed to it a collar 41, and a loose collar 42 provided with spiral gear teeth 43. A friction washer 44 is interposed between the col-

lars 41 and 42 and a spring 45 forces the loose collar toward the fixed collar, thereby maintaining frictional driving relation between the two. The spiral gear 43 is driven by a worm gear 46 affixed to the shaft 12, there being fairly loose play between these gears. In order to remove from the tack-race any improperly deposited tacks, the reservoir is provided with a rotary stripper illustrated in detail in Figs. 22 and 23. The stripper comprises a rotary shaft 47 having radiating arms 48 on each of which is loosely mounted a wiper 49. The shaft extends through the casing of the reservoir and on its outer end has a gear 50 which intermeshes with gear teeth 51 formed on the periphery of the elevator 39. Rotation of the elevator causes the stripper to revolve in the direction of the arrow in Fig. 22, and the wipers 49 being radially movable on their arms 48, wipe from the tack-race all tacks which lie in any position except that in which the shanks extend into the raceway and the heads lie flat upon the top edge. An arm 52 is formed on the reservoir and provided with a roll 53 which occupies the groove of a cam 54 affixed to the shaft 12, the said cam serving to oscillate the reservoir and tack-race upon the trunnions 36, as stated.

The delivery end of the tack-race 22 extends through a gap 55 in a tack-pick holder 56, of which a convenient form is shown in Figs. 10 to 13, and is free to move laterally back and forth in the gap. The holder 56 is pivotally mounted upon a suitable support, such as a stud 57 in the forked end of a lever 58 (see also Figs. 3 and 6). The tack-pick 23 is dove-tailed and mounted in the inner face of the holder 56 on one side of the gap 55, and a tack gage or stop 59, also dove-tailed, is similarly mounted in the holder on the other side of the gap 55. The pick 23 and stop 59 extend inwardly toward each other through a laterally-extending aperture 60 formed in the tack-race so as to intersect the wall of the discharge throat 37 where the raceway joins the latter. The inner ends of the pick and stop are beveled so as to form pointed noses with an oblique passageway therebetween to receive the shank of a tack x . When the machine is at rest, the delivery end of the tack-race is in the position in which the discharge throat 37 is under and in alinement with the driver 21 (Figs. 7, 8, 9, 12, 13, 14 and 18). The raceway is obstructed by the tack-pick when the race is in this position, but when it is moved laterally to the left, as shown in Fig. 10, the tack-pick is replaced by the stop 59. The edge of the latter is somewhat advanced over that of the pick, and so the column of tacks x in the race is free to advance a step. Upon subsequent movement of the race to the right, the nose of the pick 130

23 enters between the foremost tack and the second tack, and, by reason of its beveled end the relative movement of the race, it advances the foremost tack so that the latter 5 moves between the opposed ends of the pick and stop, and into the discharge throat 37. The tack then drops in the throat until its head engages the edge of the pick which intersects the throat (see Fig. 18). The tack 10 is now ready to be driven into the work, and the throat is in alignment with the driver 21. Figs. 3 and 6 illustrate the method of pulling the edge of the upper *a* of a shoe *b* over the edge of the inner sole *c* preparatory to inserting a fastener to hold it in place. The edge of the upper is first inserted between a pair of gripping jaws 61 and 62. The latter are then closed so as to grip the upper, and the shoe is moved manually so as to draw the upper over the edge of the innersole. The jaw 61, as shown, is formed on a nozzle 63 affixed in the end of a movable arm 64. The arm is fulcrumed on a stud 65 at the rear of the head 11, and is 20 adapted to be manually moved about its fulcrum, and to actuate tripping mechanism, hereinafter described, to render active the tack-driving mechanism. The nozzle 63 is under the driver 21 and has a central 25 throat 66 through which the tack *x* is driven to the shoe. The jaw 62 is formed on one end of the lever 67 pivotally connected at 68 to the arm 64. The other end of the lever 67 is connected by a link 69 to one arm of a bell-crank 70 mounted on a fulcrum 71 on the head 11 (see Fig. 1). The other arm of the bell-crank may be connected to one end of a treadle rod 72, and thereby moved to cause the jaw 62 to close against the jaw 61. 30 After the upper has been gripped between the jaws, it may be drawn tightly by rocking the shoe upon the heel 73 of the jaw 62. The heel 73 serves as a fulcrum, and by its aid, the upper may be drawn to any desired 35 degree of tension. When the upper is thoroughly stretched and drawn over the edge of the innersole, as shown in Figs. 3 and 6, the tack-driving mechanism may be caused to insert a tack by raising the shoe 40 bodily toward the driver 21. This causes a movement of the arm 64 about the fulcrum 65 and the actuation of the tripping mechanism already mentioned. The latter is preferably constructed so as to permit a single 45 rotation of the shaft and then to automatically disable the clutch-setting mechanism. During a single rotation of the shaft, the driver descends, driving the tack in the throat 37 through the throat 66, and into the 50 work, and then rises again to its initial position. After the driver is elevated, the cam 54 actuates the arm 52 so as to cause a lateral movement of the delivery end of the tack-race first to the left and then back to the 55 right, with the throat 37 again in alignment with the driver. This causes the advancing of another tack by the pick, into the throat 37, and the machine is again brought to a state of rest by the brake.

In order to provide against breakage of the picking mechanism, in case a tack should become disarranged in any way, the pick is mounted so as to yield to undue resistance. The nose of the pick may yield not only in the opposite direction of the movement of the tacks in the race 22, but it may yield so as to move with the race when the latter moves its throat 37 into alignment with the driver.

The tack-pick holder 56 is, as already stated, mounted on a stud 57 in the forked end of a lever 58. A spring 73 (see Fig. 12) is set into the lever 58 so as to engage the holder 56 and press the pick 23 toward the throat 37. The free end of the holder is straddled by a fixed bracket or stop 74 which permits a limited oscillation of the holder about its stud 57, and which stops the holder in opposition to the spring 73 when the forward edge of the pick slightly intersects the throat 37. In this position the pick obstructs the throat sufficiently to prevent the tack *x* therein from gravitating to the mouth of the throat. That edge of the pick which underlies the head of the tack is slightly beveled as indicated at 23°, and upon subsequent downward movement of the driver 21, the tack is forced past the pick and the latter, by reason of its beveled edge and yielding mounting, is deflected in opposition to the tension of the spring 73. The lever 58 is also held in normal position by a spring, thus enabling the holder 56 to yield bodily in addition to yielding about its pivoting stud. The lever 58 is fulcrumed between its ends upon a stud 75, and its rear end is connected with one end of a plunger rod 76. The latter is mounted to slide endwise in a bearing 77 in the head 11, and has on its inner end a head between which and the bearing 77 is a spring 78. The spring exerts its tension to draw the end of the lever 58 against the head 11 which constitutes a stop for it. In case a tack should become stuck in the raceway or in the oblique passage 115 between the ends of the pick 23 and stop 59, the two latter members are adapted to yield to the picking movement of the tack-race, and thus avoid the possibility of being damaged.

In order to close the gap in the throat 37 where the raceway enters the latter, a gate 80 is provided. The gate, as shown in Figs. 10 to 14, is mounted on the stud 57 which holds the pick holder 56 in the lever 58. The free end of the gate occupies an aperture 81 which extends laterally into the raceway, tangentially to the throat 37 where the raceway joins the latter. The gate is below the pick 23 and is of such length that when

the tack-race is in alignment with the driver, the end of the gate extends slightly more than across the raceway (Figs. 13, 14 and 18). The gate thus serves to close the 5 gap in the throat below the pick 23, so that the shank of the tack therein is inclosed, and, upon subsequent movement toward the work, is guided in an upright position. When the tack-race moves to the left to pick 10 another tack, the raceway is uncovered by the gate, which does not again obstruct the raceway until after the raceway passes under the oblique passage-way between the pick and the stop 59. 82 is a guide formed 15 on the bracket 74 for guiding the driver into the throat 37.

The tripping mechanism, hereinbefore mentioned, for controlling the clutch-setting mechanism, is preferably of such form as to 20 be actuated by the manually-movable arm 64 which carries the delivery nozzle 63. In the form shown, a lever 84, fulcrumed on the head 11 by a stud 85 (see Fig. 1), has in one end a tilting latch 86, and in the other 25 end a roll 87 which is adapted to be engaged and raised by the upper edge of the arm 64. The latch 86 is fulcrumed in the lever 84 upon a pin 88, and is adapted to overlap and engage the edge of a plate 89 affixed to 30 an extension of the controller lever 16. Below the fulcrum 88 the latch has a curved finger 90 which normally rests by gravity upon an adjustable stop screw 91. The operation of the tripping mechanism is 35 caused by raising the free end of the arm 64 as previously explained. This causes movement of the roll 87 by the arm 64 and the lever 84 is tilted upon its fulcrum 85, lowering the fulcrum 88 in the rear end of the 40 said lever. The finger 90 in its downward movement is deflected by the stop 91, thus causing oscillation of the latch 86 about its fulcrum. Meanwhile, the latch, by reason 45 of its engagement with the plate 89, tilts the controller 16 upon its pivoting stud 18 against the tension of a spring 92, so as to disengage it from the normally operative clutch-setting mechanism 15. The clutch members 14 are then moved into operative 50 engagement with each other and the shaft 12 is set in motion. The stop 91 is so adjusted that it causes the latch 86 to move out of engagement with the plate 89 immediately after the controller 16 is disengaged 55 from the mechanism 15. The spring 92 then returns the controller toward its former position in engagement with the mechanism 15, and when the latter, which rotates with the shaft 12, completes a single revolution, 60 it is once more rendered inoperative by the controller. The brake mechanism then operates as previously described, and brings the machine to a stop after a complete cycle of operations. When the shoe is afterward 65 lowered away from the jaws 61 and 62, the

arm 64 resumes its former position, followed by the lever 84 and latch 86 which hooks over the edge of the plate 89 and is again in position to retract the controller 15 as described.

70

I claim:

1. In a tack-inserting mechanism, a tack race, a tack pick arranged to cooperate therewith, a movable support for the pick, means for causing relative picking movement of the pick and race to move a tack forward, and yielding means acting on said support to move the pick transversely of the picking movement, whereby the pick is held in position to support the advanced tack. 75

2. In a tack inserting mechanism, a tack race, a tack pick, one movable relatively to the other, said tack pick being arranged by reason of the relative movement of the race and pick to enter between the foremost tack 85 and the remaining tacks in the race and to advance the foremost tack, an oppositely arranged stop member for the tacks, and a gate arranged below the tack pick and projecting in the same direction therewith for 90 obstructing the tack race between the pick and the mouth of the throat, said pick, stop member, and gate being connected with each other and yielding as a unit.

3. In a tack inserting mechanism, a tack race having a discharge throat, a yielding tack pick arranged by reason of the relative movement of the race and pick to enter between the foremost tack and remaining tacks in the race, and to advance the foremost 100 tack to the discharge throat and underlie its head so as to support it therein, an oppositely arranged stop member for the tacks, and a gate below the tack pick and the stop member for obstructing the race between the 105 throat and remaining tacks.

4. In a tack inserting mechanism, a tack race having a discharge throat, a support, a tack pick mounted on the support, a stop member for the tacks, and a tack-race gate 110 mounted on the support, said pick being arranged by reason of the relative movement of the race and pick to enter between the foremost tack and remaining tacks in the race and to obstruct the race and advance 115 the foremost tack to and support it by its head in the discharge throat, said stop member being arranged to permit the gravity feed of the tacks when the tack pick is withdrawn, and the gate being arranged to enter between the shanks of the advanced tack and remaining tacks and to confine the shank of the advanced tack within the discharge throat. 120

5. In a tack inserting mechanism, a tack 125 race having a discharge throat, a yielding tack pick arranged to enter between the foremost tack and remaining tacks in the race and to advance the foremost tack into the throat with yielding pressure, a yielding 130

- support for the tack pick, and a gate mounted on the yielding support so as to obstruct the tack race behind the shank of the advanced tack and confine the latter within the throat. 5
6. In a tack inserting mechanism, a tack race having a discharge throat, a support at one side of the race and arranged to yield away therefrom, a tack pick yieldingly mounted on the yielding support and having a tapered nose for entering between the shanks of the foremost tack and remaining tacks in the race and for advancing the foremost tack into the discharge throat and supporting it yieldingly therein, said race having a transversely-extending intersecting passageway, and a gate mounted on the yielding support and extending into the said passageway so as to enter between the shanks of the advanced tack and the remaining tacks and confine the former in the throat. 10 15 20 25
7. In a tack inserting mechanism, a tack race having a discharge throat, a stationary tack pick having a tapered nose by which the shank under the head of the foremost tack in the race may be engaged and advanced into the throat, said race having a transversely-extending passageway tangential to that wall of the throat through which the tack enters, and a stationary gate extending into said passageway and arranged to extend across the race tangentially to the throat and confine the shank of a tack in said throat, said tack pick and said gate acting at substantially the same time on the same tack. 30 35 40 45
8. In a tack-inserting mechanism, a tack race having a discharge throat, a tack pick arranged to coöperate therewith, a support for said pick, a pivot member for said support at one side of the delivery end of the race, said support being movable about the axis of said pivot member whereby the pick is made capable of movement substantially parallel to the length of the race, means for causing relative picking movement of the race and pick transversely of the race, and yielding means acting on said support to cause the pick to support a tack in the throat. 50
9. In a tack inserting mechanism, a tack pick having a tapered nose and yieldingly mounted so that the nose may yield in two directions transverse to each other, a stop rigidly connected to the pick so as to form, with the nose, a passageway oblique to both of said directions of yielding, for the passage of the shank of a tack, a tack race for conducting tacks to one side of the tack pick in a direction substantially parallel to one of said directions of yielding, said tack race and said tack pick and stop being laterally movable one relatively to the other in a direction substantially parallel to the other 55 60 65
- direction of yielding, and a discharge throat at the end of the race-way on the other side of the tack pick into which the tacks are advanced one by one with yielding pressure by the pick when the race and the tack pick 70 and stop are moved laterally back and forth relatively to each other. 75
10. In a tack inserting mechanism, a tack race having a discharge throat, a driver movable through said throat across the delivery end of said race, and means arranged to feed a tack from said race into said throat and support said tack in said throat until the tack is engaged by said driver, said means being arranged to be displaced from 80 85 90 95 100 105 110 115 120 125 130
- tack-supporting position by the driven tack. 125
11. In a tack inserting mechanism, a tack race having a discharge throat, a driver movable through said throat across the delivery end of said race, and means arranged to feed a tack from said race into said throat, said means having a yielding tack-engaging element arranged to support the tack in said race until the tack is engaged by said driver, said tack-engaging element being movable from tack-supporting position by the driven tack. 130
12. In a tack inserting mechanism, a tack race having a discharge throat, a yielding support, a yielding tack pick normally intersecting the wall of the throat where the raceway joins the latter, said pick being arranged to advance the tacks one by one into the throat and support them therein by yielding tension, and a gate mounted on said yielding support and normally intersecting the raceway at a point tangent to the wall of the throat where the raceway joins the latter. 135
13. In a tack inserting mechanism, a reciprocatory driver, a laterally-movable tack race having a discharge throat normally in alinement with the driver, and a laterally yielding tack pick for coöperating with the tack race to advance the foremost tack into the throat, said pick having a beveled edge normally intersecting one side of the throat for supporting the tack therein. 140
14. In a tack inserting mechanism, a normally elevated reciprocatory driver, a delivery nozzle in alinement therewith, a laterally-movable tack race having a throat movable to and from a position in alinement with and between the driver and the nozzle, and a laterally-yielding tack pick arranged to advance the foremost tack in the race into said throat and yieldingly supporting said tack in the throat. 145
15. In a tack inserting mechanism, a reciprocatory driver, a yielding tack pick having a beveled edge intersecting the path of the driver, and a tack race for conducting tacks to the tack pick, means for moving said tack pick and said tack race one rela- 150

tively to the other to cause the pick to engage the shank of a tack and advance it to a position in alignment with the driver, said tack race having a throat to receive the advance tack and to guide the driver.

16. A tack inserting mechanism comprising a tack race having a throat, a tack pick, means for effecting a relative movement of the tack pick and said raceway to feed the tack to the throat piece, and means for mounting said tack pick so that it may yield laterally and yieldingly support a tack fed thereby in the throat.

17. In a tack-inserting mechanism, a tack race having a discharge throat, a tack pick

arranged to coöperate therewith, movable means supporting said pick and rendering the same capable of movement transversely of the race and of movement substantially parallel to the race, means for causing relative picking movement of the pick and race transversely of the race, and yielding means for holing the pick normally in position to support a tack in the throat.

In testimony whereof I have affixed my signature, in presence of two witnesses.

HARRIE A. BALLARD.
